flows upwardly through these tubes from the rear to the front end of the combustion chamber.

In the present illustration I have shown 5 three of the tubes 38, though any desired number of said tubes may be provided.

The bricks or units 40 constituting the arch wall which is suspended from the tubes 38 are formed of refractory material. Preferably, these bricks have the configuration illustrated in Figure 4 of the drawings, and are produced from the refractory material, while in a plastic condition, by means of a suitable mold. Thus each of the bricks is 10 provided with a convex lower face 41, which, when the bricks are arranged in assembled position upon the tubes 38, has its intermediate portion disposed below the plane of the lowest surfaces of the tubes. The upper face 15 of each brick is preferably, though not necessarily, recessed, as at 42. The longitudinal side portions of the bricks for substantially the length of the recess or cavity 42 are of increased width to provide reinforcing ribs 20 or flanges 43 which constitute the opposite side walls of said cavity. Upon the surface 25 of the recess or cavity 42 suitable indicia 44 is molded in the formation of the brick, such indicia denoting the type and size of the 30 brick in accordance with a legendary table upon which the different brick sizes are tabulated. It will be seen that the ribs or flanges 43 protect this indicia from wear, and possible obliteration when the bricks are piled 35 upon each other for shipment. While I have found this feature to be one of considerable practical convenience, it is, nevertheless, to be understood that the provision of such indicia may be dispensed with, and that the 40 brick need not necessarily be provided with the side flanges 43.

Each end of the brick 40 is provided with a transversely extending seat 45 in the convex face 41, said seating surface being arcuately curved longitudinally of the brick upon a radius which is somewhat greater than the radius of the water tube 38. It will thus be apparent that when the brick is arranged in suspended relation to the tube, the seating face 45 thereof will have a single point of tangential contact upon the periphery of the tube intermediate of the upper and lower edges of the seating surface.

Each end face of the brick beyond the seating surface 45 is convexly curved, as at 48, the radius of this curved end face, the seat 45 and tube 38 having such relation to each other that when one end of the brick is engaged upon the upper side of one of the tubes 38 the bottom face of the brick will have contact upon the periphery of the tube across the entire width of the brick.

To the inner side sheets 32 of the water legs the spaced cylindrical supporting trunnions 50 are fixed, preferably by electrically

welding said trunnions to the metal sheets.

In assembling the baffle bricks or units to produce the furnace arch, the outer longitudinally extending rows of bricks are arranged with their seating surfaces 45 engaged upon the upper portions of the outer tubes 38 at one side of the tube centers. The other ends of these bricks in the outer rows are supported by the trunnions 50, the concave seating faces 45 at one end of the 70 bricks in this outer row contacting upon the ends of the trunnions at the upper sides thereof, the faces 45 extending inwardly and downwardly from the ends of the trunnions to the convex bottom faces 41 of the 75 bricks.

As is well known in such locomotive furnace structures, the side sheets 32 of the water legs are inclined both vertically and longitudinally, and have their upper portions curved inwardly to meet the crown sheet 35. However, by providing the bricks 40 with the transversely convex end faces 48 these end faces will substantially clear 80 the inner faces of the side sheets of the 85 water legs so that the bricks may be easily fitted in place or removed. The concave sides or faces 45 of the brick prevent the pocketing of the products of combustion 90 adjacent to the furnace sides and the supporting trunnions below the brick and serve to direct such products either downwardly in part into the combustion chamber, or to permit them to pass upwardly between the furnace sides and the brick ends thereby obviating the possibility of slag formation, 95 the deterioration of the ends of the brick or of the furnace sides by concentrated excessive heating thereof.

The inner or intermediate rows of bricks 100 are arranged in suspended relation between the adjacent tubes 38 with the convex end faces 48 of the bricks in each of the rows opposed to the convex end faces of the bricks in an adjacent row, which are engaged 105 upon the same water tube. The convex end faces of the bricks in adjacent rows do not, however, contact with each other, and the bricks are at all times free and independent, so that they can be separately removed and replaced at any time. As the construction 110 of the brick ends is identical, either end of the bricks of the outer rows can be engaged with the supporting trunnions on the water legs, and loss of time in fitting or assembling the outer rows of bricks in place is thereby obviated. Thus it will be apparent 115 that with a brick of this particular construction either end of the brick may be properly positioned upon the water tubes 38 or upon the trunnions 50 so as to produce a substantially completely closed arch wall between the water legs. Therefore, in the production 120 of a furnace arch of the type disclosed in my issued patent the same brick pattern 125 130

elements, and each of said end portions of the baffle unit at the upper side thereof and above said tube engaging surface terminating in an end face having a continuous convex curvature extending across the entire width of the unit whereby the side units of the arch wall may be properly positioned upon said supporting elements and in close relation with the side sheets of the water legs.

2. In a locomotive fire box having vertically disposed water legs at the sides thereof, and spaced water tubes extending through the combustion chamber; an arch wall consisting of baffle bricks all of identically the same form and construction, supporting trunnions fixed to the side sheets of the vertically disposed water legs, each baffle brick having a transversely extending longitudinally concaved seating face on its under side at each of its ends for continuous contact of each end face across the entire width of the brick upon one of the water tubes, or

for engagement with one of the trunnions, whereby said units may be arranged upon and between said tubes and between the outermost tubes and the side sheets in a common transverse horizontal plane to provide a substantially closed wall.

3. A baffle unit for locomotive fire box arches formed of refractory material and provided at each of its ends on the under side thereof with a continuous uninterrupted surface extending transversely across the full width of the unit for close seating engagement upon a water circulating tube extending through the fire box or upon a supporting trunnion fixed to one of the side sheets of the fire box, and each end of said unit above said tube engaging surface having a convex end face describing a continuous arc extending between the opposite edge or side faces of the unit.

In testimony that I claim the foregoing as my invention, I have signed my name.

JOHN E. MUHLFELD
